assignor to Graviner Manufacturing Company
Limited, Osterley, Isleworth, Middlesex, Eng-
land

Application June 28, 1941, Serial No. 400,300
In Great Britain April 22, 1940

8 Claims. (Cl. 169—11)

This invention has for its object the improvement in fire extinguishing system devices more particularly for use upon aircraft.

Fluid containers such as fire extinguishers for example of the character shown in Figure 1 of United States Patent No. 2,143,132 are sometimes required to have a high rate of discharge whereby a fire source may rapidly and automatically be sprayed with fire extinguishing fluid, for example in accidental crashes of an aircraft, the container also being provided with slow discharge means for hand use when a local fire breaks out for example in a compartment of an aircraft.

In the installation of fire extinguishing equipment of the kind disclosed in the above mentioned patent particularly upon aircraft there is sometimes difficulty in finding space for the extinguishers in positions where they are accessible to the personnel for slow discharge or hand use, and it has been proposed to mount the extinguisher out of reach of members of the personnel. It is an object of the invention to provide a nozzle device in the discharge conduit in such systems, said device being detachable for spraying fire extinguishing fluid upon a fire which might occur at a particular point in an aircraft, such as in the pilot's or gunner's compartment.

Another object of the invention is to provide a nozzle device in fire extinguishing fluid conduits which nozzle device is adapted to permit a high rate of fluid discharge when attached to a co-acting socket device and is further adapted to restrict the rate of discharge from the fluid supply when the nozzle device is detached from its co-acting socket so as to spray the fire extinguishing fluid jet upon a fire in the personnel compartment.

A further object of the invention is to provide a valve device in said nozzle which is adapted to be displaced when the nozzle is inserted in its co-acting socket so as to permit a high rate of fluid discharge through the nozzle. Said valve being furthermore adapted to be displaced when the nozzle is detached from its co-acting socket so as to move on to a valve seating or like arrangement to restrict its rate of discharge from the nozzle to a suitably low rate of discharge.

A still further object of the invention is to provide said socket device with an abutment or like arrangement which effects displacement of the valve in the nozzle when the nozzle is inserted in its co-acting socket, the valve and nozzle

device being so constructed that when the valve is displaced in this manner the sectional area of the conduit through the nozzle and socket device is substantially equal to the area of the internal diameter of the discharge conduit from the fluid supply container.

When using fire extinguishers containing liquids or fluids which may affect the personnel owing to their toxicity it is highly desirable to limit the discharge of fluid from such fire extinguisher to the absolute minimum required for extinguishing a fire and according to one object of the invention an auxiliary socket device is provided for the nozzle which device has a jettisoning conduit attached thereto so that by inserting the nozzle device in said auxiliary socket after a fire has been extinguished the excess amount of fire extinguishing fluid can be discharged outside the personnel compartment, thereby reducing the risk of personnel being affected by the toxic fumes generated by the said fire extinguishing fluids.

Various means may be adopted for detachably securing said nozzle and socket device together but preferably a bayonet type of pin and socket joint is employed for this purpose as rapidity of detachment is necessary, more especially when fire extinguishing systems of the kind described above are used upon aircraft.

Various additional objects and features of the invention will be more fully described with reference to the accompanying drawings which show one embodiment of the invention by way of example. Similar reference numerals relate to like parts in all the figures of the drawings.

Figure 1 shows an aircraft in partial sectional elevation.

Figure 2 is a sectional elevation of the nozzle and socket shown in the secured together position.

Figure 3 is a partial sectional elevation of the nozzle shown detached from the socket.

Figure 4 is a partial sectional elevation of the socket.

Figure 5 is a view similar to Figure 4 showing a modified form of socket.

Referring to Figure 1 in the drawings, numeral 2 denotes the fuselage of an aircraft and 3 the engine thereof. A fluid conduit type of fitting 4 is secured in the fireproof bulkhead of the aircraft and is connected by the conduit 11 to the socket device 5 into which the nozzle 6 is secured. An auxiliary socket 5a is provided with a jettisoning pipe or conduit 5b said pipe extend-

ing to the external surface of the fuselage of the aircraft.

A fire extinguishing fluid supply container is connected to a conduit 8 extending therefrom to a connector fitting 9 secured in the aircraft compartment. This fitting 9 is connected to a flexible conduit 10 the other end of which is connected to the nozzle 6 which flexible conduit portion permits detachment and re-insertion of the nozzle 6 into the socket 5. A conduit portion 11 extends from the socket 5 to the fitting 4 and a known type of perforated fire extinguishing fluid distributing piping 13 extends from this fitting over the engine 3.

Referring now to Figures 2, 3 and 4, the nozzle device comprises a barrel portion 14 screwed into a nozzle sleeve 15, said nozzle sleeve having a bore 16 and a discharge orifice 17. The nozzle sleeve is provided with a valve device 18 which is provided with grooves 19.

The valve 18 is furthermore provided with a machined valve type of seating 20, adapted to contact with a correspondingly shaped valve seating 21 formed adjacent the discharge orifice 17 of the nozzle sleeve 15.

The socket 5 is provided with a spider-shaped fitting 22 which is forced into the tapered bore of the socket 5 so as to become firmly fixed in the position shown in Figure 2. The spider 22 is provided with a stem 23 adapted to project 30 through orifice 17 of the nozzle sleeve 15 and to contact valve 18 and push this away from the valve seating 21 in nozzle sleeve 15, when the nozzle is secured to socket 5 as shown in Figure 2.

From the design of the device the sectional area of the discharge conduit 8 will be known and the sectional area of the passages through grooves 19 and through the unobstructed portion of orifice 17 and other parts of the device must not be less than this area, so that full bore discharge of fluid can be obtained through the device.

Referring to Figures 3 and 4, as will be seen socket 5 is provided with bayonet type of joint slots 24 with which pins 25 on the nozzle sleeve 15 are adapted to engage in such a manner that the similarly tapered surfaces 26a of socket 5 and 26 of nozzle sleeve 15 are forced into substantially fluid-tight contact.

Upon detachment of nozzle sleeve 15 from the socket 5 valve 18 is free to move towards the discharge orifice 17 of the nozzle sleeve as soon as liquid pressure is applied from the supply source 7. As a result of contact between the valve seatings 20 and 21 liquid discharge through 50 grooves 19 will be prevented but valve 18 is provided with a slow rate discharge orifice 27 through which liquid can be discharged while the nozzle is held in the hand by an operator, the jet being then played upon a fire, for example, in a personnel compartment to extinguish the same.

Referring now to Figure 5 the socket comprises two parts 55 and 56 which are screw-threaded so as to be detachable at 57. A cavity 65 55 is formed in the part 56 into which a leather, rubber or other resilient material ring 59 is adapted to be secured and firmly clamped so as to project into fluid-tight contact with the end of the nozzle sleeve 15. The provision of such 70 resilient material fluid leakage reducing device obviates the necessity for accurate fitting between the socket 5 and the nozzle sleeve 15.

It is an essential requirement that in the case 75 of fires originating upon aero engines the fire

extinguishing fluid be discharged as rapidly as possible so as to inundate the engine with fire extinguishing fluid to ensure extinction of fires upon whatever part of the engine they might originate. Consequently, the discharge rates through the conduits 8, 10 and 11 are of the order of one pint of the fluid in liquid form in 2 to 3 seconds, depending to some extent upon the length of the conduit and also upon the pressure in the fluid container 7.

The contents of fire extinguishing fluid container 7 of one known type is three pints and the discharge period is between 6 to 9 seconds, from which it will be appreciated that the discharge of the whole of the contents of such extinguishers in a personnel compartment of an aircraft would probably result in that the occupants of the compartment might be rendered unconscious thereby losing control of the aircraft.

20 The discharge rate through orifice 27 in valve 18 is of the order of one pint of liquid in 15 to 20 seconds and if a fire occurs in a personnel compartment it is possible for an occupant to detach nozzle 6 from socket 5 and effect discharge of extinguisher 7 by means of the control device 25 normally provided upon the aircraft instrument panel for the occupant's use.

The liquid jet would then be played upon the fire until it is extinguished, an operation which should not normally take more than 5 to 10 seconds. Excess fire extinguishing fluid can then be discharged through auxiliary socket 5a and discharge conduit 5b outside the aircraft whereby discomfort and danger to the occupant by excess fire extinguishing fluid fumes is greatly reduced.

Having thus fully described my invention, what I claim as new and desire to protect by Letters Patent is:

1. In a fire extinguishing fluid discharge system, a fluid supply under pressure, a conduit from said supply to a fire risk source, means for effecting discharge of said supply, a nozzle in said conduit, a socket device to which said nozzle is adapted to be detachably secured, means associated with said socket device for permitting a high rate of fluid discharge when the nozzle is secured thereto and means associated with said nozzle device for restricting the rate of discharge therefrom when the nozzle is detached from said socket.

2. In a fire extinguishing fluid discharge system, a fluid supply under pressure, a conduit from said supply to a fire risk source, a nozzle in said conduit, a socket device to which said nozzle is adapted to be detachably secured, a valve means in said nozzle and abutment means in said socket adapted to displace said valve means when said socket device and said nozzle are secured together to permit a high rate of fluid discharge through said nozzle.

3. In a fire extinguishing fluid discharge system, a fluid supply under pressure, a conduit from said supply to a fire risk source, a nozzle in said conduit, a socket to which said nozzle is adapted to be detachably secured, valve means in said nozzle, said valve means having a slow rate discharge orifice through which the fluid discharges when said nozzle is detached from said socket and means in said socket for unseating the valve of said valve means when said nozzle is attached to said socket to increase the discharge rate through said nozzle.

4. In a fire extinguishing fluid discharge system, a fluid supply under pressure, a conduit

from said supply to a fire risk source, a nozzle in said conduit, bayonet type of pins upon said nozzle, a socket device, bayonet type of slots in said device, and liquid-tight surfaces upon said nozzle and upon said socket adapted to be forced into liquid-tight contact when said bayonet pin and slot arrangement is forced into engagement, a valve device in said nozzle and means to increase the rate of flow through said valve device when it is inserted into said socket from the rate when it is out of said socket.

5. In a fire extinguishing fluid discharge system, a fluid supply under pressure, means for effecting discharge of said supply, a conduit from said supply to a fire risk source, a nozzle device in said conduit, a socket device and means for detachably securing said nozzle and socket device together, means for permitting a high rate of discharge through said nozzle and socket when secured together, means for restricting the rate of discharge from said nozzle when detached from said socket, an auxiliary socket to which said nozzle can be detachably secured and a conduit from said auxiliary socket to discharge surplus fire extinguishing fluid externally to a personnel containing compartment.

6. In a fire extinguishing fluid discharge system for use on aircraft, a fluid supply under pressure, a conduit from said supply to a fire risk

source adjacent to the engine of the aircraft, a socket device in said conduit, a nozzle in the portion of said conduit connected to said fluid supply, said socket device being adapted to snuggly receive and detachably retain said nozzle for passing the fluid from said supply to said fire risk source, said nozzle and said socket being positioned adjacent to the operator of the aircraft so that said nozzle may be removed from said socket and fluid therefrom sprayed in other parts of the aircraft to prevent or subdue fire and a jettisoning pipe and socket for unloading fluid and fumes that may be sprayed around the operator's compartment, said last socket being adapted to receive said nozzle.

7. In a fire extinguishing fluid discharge system as set forth in claim 6 further comprising means in said nozzle and said socket for increasing the fluid discharge rate through said nozzle when said nozzle is secured in said socket from the rate when said nozzle is out of said socket.

8. In a fire extinguishing fluid discharge system as set forth in claim 6 further comprising a valve member positioned in said nozzle, said valve member having a hole extending through the body thereof through which the said fluid discharges solely when said nozzle is out of said socket.

ANDERS MATHISEN.
